UNITED STATES PATENT OFFICE

99,296

DESIGN FOR A HAIR DRIER

Emanuel E. Norquist, Kansas City, Mo.

Application October 25, 1935, Serial No. 59,215

Term of patent 7 years

To all whom it may concern:

Be it known that I, Emanuel E. Norquist, a citizen of the United States, residing at Kansas City, in the county of Jackson and State of Missouri, have invented a new, original, and ornamental Design for a Hair Drier, of which the following is a specification, reference being had to the accompanying drawing, forming part thereof, in which,

I claim:

The ornamental design for a hair drier substantially as shown.

In testimony whereof, I affix my signature.

EMANUEL E. NORQUIST.
